UNITED STATES PATENT OFFICE.

EDWARD G. CLINE, OF MILWAUKEE, WISCONSIN, ASSIGNED TO THE LAKWOOD ENGINEERING COMPANY, OF CLEVELAND, OHIO, A CORPORATION OF OHIO.

EDWARD G. CLINE.

1,295,850.

Specification of Letters Patent. Patented Mar. 4, 1919.

Application filed August 10, 1916. Serial No. 231,862.

To all whom it may concern:

Be it known that I, EDWARD G. CLINE, a citizen of the United States, residing at Milwaukee, in the county of Milwaukee and State of Wisconsin, have invented certain new and useful Improvements in Road-Forms, of which the following is a specification, reference being had to the accompanying drawing, forming a part thereof.

10 This invention relates to road forms for making concrete roads and the like and the object of the invention is to improve the construction of road forms in the manner to be hereinafter described and claimed.

15 Heretofore such forms have been constructed with flat top surfaces transversely of the forms and, as the tops of the forms are used as guides or templates for the road surface, if a form tipped, the elevation of the 20 road surface would be changed. One of the principal objects of this invention is to provide a form having a top surface of such a character that the tipping of a form does not change the position of the top surface of the 25 form. Other improvements and advantages will be pointed out herein in this specification.

Referring to the drawings which accompany this specification and form a part hereof, which drawings illustrate an embodiment of this invention, and in which drawings the same reference characters are used to designate the same parts wherever they may appear in each of the several views.

30 Figure 1 is a plan view, on a small scale, of the subgrade of a road with the forms and some supports in place; Fig. 2 is a cross section on the line 2—2 on Fig. 1, looking in the direction indicated by the arrow; Fig. 3 is an elevation of a support, looking in the direction indicated by the arrow on Fig. 2; and Fig. 4 is a side elevation of a form, looking in the direction indicated by the arrow on Fig. 2.

35 Referring to the drawings, the reference numeral 1 designates forms of which a sufficient number are provided to meet the requirements of the rapidity with which the work is being completed as it is not ordinarily intended to leave the forms as a part 40 of a completed road or other construction, though they can be so used if desired. Ordinarily the forms are removed, after the concrete has set, and they and their supports are placed ahead of other forms.

A form 1 is provided with a retaining wall 2 and a flat point top surface 3. The specific cross sectional shape adopted to obtain this flat point top surface is immaterial but it can be readily obtained, as shown by the drawings, by forming an arc of a circle with the sheet metal at the top of the retaining wall 2. As a matter of convenience in handling the form 1 on the work the bottom of the retaining wall 2 is provided with a similar flat point top surface 4 so that the top can be used either for the top or bottom and the bottom can be used either for the bottom or the top. This is a matter of importance on the job because a form does not have to be turned end for end but only rolled over to place it on the supports if it does not lie properly positioned when deposited on the ground. The forms can be made cheaply by taking a sheet of metal of the required length, width and thickness and forming tubular beads 5 and 6 on its longitudinal edges. When these tubular beads are circular in cross section, as illustrated by the drawings, the greatest strength is obtained both vertically and laterally for the amount of metal employed and the insides of the beads form excellent surfaces to bear on the supports. The beads may be strengthened by pipes or rods 7 for whatever distance is desired and these pipes or rods may project to serve as dowels 8 to enter the beads of adjacent forms to form fishplates to strengthen the track surface formed by the forms as the forms are also used as tracks for road making machines.

The supports 9 are preferably made from Y-bar as this form of bar has two flat surfaces at right angles and so disposed with respect to each other that a support can be driven into the ground without liability of twisting or turning, in other words, it keeps its alignment while being driven. The support has a hook 10 to catch behind a bead and a brace 11 to prevent outward movement of the retaining wall 2, and it is preferred to sharpen it only on the cross bar of the Y and not on the stem of the Y, as clearly shown by Figs. 2 and 3 of the drawings, to prevent displacement of the support 10 when it is being driven into the ground. A simple method of making the hook 10 and the brace 11 is to rivet a piece of sheet metal to the support and provide a depression 12 into which a bead can set.

One or more holes 13 can be provided in a support to receive bars or pipes 14 to afford bearing surface in soft ground.

The advantages of the construction are obvious. Even if the retaining wall 2 is not perfectly vertical, the uppermost top of the form remains in the same plane. There are no open channels to fill with cement. The form can be used with either bead up and 10 has great lateral and vertical rigidity. The hooks 10 prevent the forms from being accidentally displaced from the supports when being moved endwise to engage dowels. The line point top surface of the 15 form prevents cement mortar from accumulating thereon and making an uneven surface for the road making machine or templet, if a templet be used.

What is claimed is:

20 1. A road form provided with a retaining wall having at its upper edge a line point top surface.

A road form provided with a retaining

wall and having at its upper and lower edges line point top surfaces. 25

3. A road form of sheet metal provided with a retaining wall and tubular beads at its top and bottom edges.

4. A road form of sheet metal provided with a retaining wall and tubular beads at 30 its top and bottom edges and dowels extending from the beads.

5. A road form provided with a retaining wall having at its upper edge a line point top surface in combination with a support adapted to retain the line point top surface of the form in the same plane whether the retaining wall is vertical or inclined. 35

6. A support for a road form made from a T-bar and sharpened on the cross bar of the T, the support being provided with a hole adapted to receive a bar or pipe to afford bearing surface in soft ground. 40

In witness whereof I hereunto affix my signature.

EDWARD G. CARR
